PLASTIC MERCHANTISING CONTAINER
OR THE LIKE

Richard K. Shelby, Downers Grove, Ill., assignor to Monsanto Company, St. Louis, Mo., a corporation of Delaware

Filed Aug. 26, 1964, Ser. No. 81,449

Term of patent 14 years

(Cl. D58—12.6)

FIG. 1

FIG. 2

FIG. 4

FIG. 1 is a perspective view of a plastic merchandising container or the like, showing my new design;

FIG. 2 is a side elevational view;

FIG. 3 is a top plan view; and

FIG. 4 is a bottom plan view thereof.

The dominant features of my design reside in the portions shown in full lines.

I claim:

The ornamental design for a plastic merchandising container or the like, as shown and described.
